UNITED STATES PATENT OFFICE.

AUGUSTUS HERATH AND IVER HULTMAN, OF SCHENECTADY, NEW YORK.

AUTOMATIC TRIPPING SAFETY DEVICE FOR ELECTRIC MOTORS.

No. 863,177.

Specification of Letters Patent.

Patented Aug. 13, 1907.

Application filed August 7, 1905. Serial No. 273,131.

To all whom it may concern:

Be it known that we, AUGUSTUS HERATH and IVER HULTMAN, citizens of the United States, residing at Schenectady, in the county of Schenectady and State 5 of New York, have invented a new and useful Automatic Tripping Safety Device for Electric Motors, of which the following is a specification.

Our invention relates to improvements in automatic tripping safety devices for electric motors, and pertains 10 particularly to motors used on electrically propelled railway cars.

The object of our invention is to provide an electrically operated mechanism whereby the pinion carried by the motor is thrown out of gear with the gear 15 carried by the axle when the current has become grounded by the wearing of the different parts and the current is cut off from the motor. The motor is thrown out of gear with the driving axle, thus preventing the continued working of the different parts of the motor 20 as the car is hauled under other power and also preventing the destruction of the mechanical parts of the motor.

Another object of my invention is to provide a more simple, cheap and compact device of this character 25 which is readily applicable to any trolley car in which the motor is swingingly supported upon the driving axle, which is the almost universal method of supporting the motor.

In the accompanying drawings: Figure 1 is a longitudinal vertical sectional view of that portion of the car carrying the motor and showing the motor supported in a position with the pinion in engagement with the gear carried by the axle and driving the same and my device holding the motor in said position; Fig. 2 is a 35 longitudinal vertical sectional view; the same as Fig. 1, only showing the electrical tripping device thrown and the motor swung downwardly with the pinion cut of gear with the gear carried by the axle, thus allowing the axle to rotate without moving the parts of the motor; Fig. 3 is a rear end view of Fig. 1; Fig. 4 is a top plan view of the switch used on motor cars, and showing an auxiliary switch whereby the same is operated when the current is cut off from the motor; Fig. 5 is a transverse vertical sectional view taken on the line 45 $z-z$ of Fig. 4; Fig. 6 is a bottom plan view of Fig. 4; and Fig. 7 is a diagrammatical view of the main and auxiliary circuits showing motor in action. Fig. 8 is a diagrammatical view of the main and auxiliary circuits showing the motor out of action.

Referring now to the drawings, 1 represents the axle of the trolley car, which, as in all electrically propelled vehicles, is mounted in journals and has the wheels 2 rigidly carried thereby. Adjacent thereto is the motor 3, which is mounted within the usual casting 4, and, as shown, is provided with an arm 5 extending

ing to and surrounding the shaft by means of which the motor is supported at that end and permitted to have a limited oscillating movement on the axle, as will be hereinafter more fully described. The opposite end of the motor casing 4 is provided with a horizontally 60 extending lug 6, through which passes the vertically extending bolt 7, which is rigidly supported in a vertical position by the portion or beam 8 of the bogie of the car. The opening in the lug 6 is such that the same is free to move freely up and down upon the bolt 7. Surrounding said bolt, above and below the said lug, are coil-springs 9 and 10 which normally hold that end of the motor casing in the position shown in Fig. 1; but permit the same to have an upward and downward movement to allow for the jolting and rocking of the 70 car and prevent injury to the motor.

The motor 3 is of any well known construction and is provided with the usual shaft 11, which extends outwardly through the end of the casing 4, and is provided with a pinion 12 that meshes with an enlarged gear 13, 75 rigidly secured on the axle 1, and by means of which the axle is rotated, thus causing the car to be propelled.

The arm 5 of the motor casing has formed therein a circular opening in which is located a disk 5 $\times$ through which is formed on one side of its center a bearing for 80 the axle 1. By reason of this construction it will be readily understood that so long as the disk 5 $\times$ is held in the position in which it is shown in Fig. 1 the distance between the center of the axle and the armature shaft will be such that the pinion 12 will remain in mesh 85 with the gear 13, but if the disk 5 $\times$ is turned or permitted to turn in the opening in which it is located to the position in which it is shown in Fig. 2, the motor will be moved away from the axle so as to separate the pinion 12 from the gear 13, thus dis-connecting the 90 motor from the axle.

14 are the field coils and 15 is the armature of the motor. 16 are the pole pieces of usual construction.

17 are contact pieces carried on the pole pieces and having their ends extending inward so as to be nearly 95 but not quite in contact with the armature. These contacts 17 are insulated from the pole pieces 16 and are terminals of the circuit of an electro-magnet for operating releasing mechanism hereinafter described, the pole pieces 16 forming the other terminal. 100

In motors as ordinarily constructed, any wearing of the bearings of the armature shaft, sufficient to permit the armature windings to come in contact with the pole pieces is liable to cause a short circuit and injure the motor. In the construction herein shown and described, such contact of the armature windings with the pole pieces 16 and the contacts 17 closes a circuit through the electro-magnetic device, as hereinafter described, by which the device holding the disk 5 $\times$ in position is tripped, permitting the disk to turn to the 110

position in which it is shown in Fig. 2 and causing the pinion 12 and gear 13 to be dis-engaged as above described.

In order to sustain the motor when the disk 5X is permitted to rotate, an arm 18, secured to its upper portion is pivotally connected to the body 22 of the car, the arm 18 being so formed that its pivot is in a plane about midway between the axle 1 and the normal portion of the armature shaft 11.

- 10 Secured to the disk 5X is a radial arm 19, normally lying in a horizontal plane as shown in Fig. 1, this arm extending through a slot 20 in the arm 5. The arm 19 is held in a normal position by a toggle lever 21, consisting of two links connected at 24, having its lower 15 end pivoted to the arm 19 and its upper end pivoted to the car body 22, this toggle lever when in extended position holding the end of arm 19 firmly down, the links of the toggle lever when in this position being in a straight line or bent slightly, past a straight line in a 20 direction away from the motor. A spring 25 is connected at one end to the arm 19 and at the other end to the car body 22 at a point near the pivot of the arm 18, this spring being adapted when the toggle lever 21 is tripped, as hereinafter described, to draw the end of 25 the arm 19 upward, rotating the disk 5X and causing the motor to be moved away from the axle into the position in which the parts are shown in Fig. 2. Two springs 25 are preferably used, being connected with the arm 19 through a cross bar 26, as shown in Fig. 3.
- 30 28 is the tripping mechanism for tripping the toggle lever 21 to permit the spring 25 to act to rotate the disk 5X. The tripping mechanism comprises a magnet or solenoid 29, secured to the car body 22 and having a core or armature 30 connected with a lever 31 pivoted 35 at 32 and having its end 33 wedge shaped, as shown, and arranged in position to serve as a stop for the joint 24 of the toggle lever 21 when it is in the position in which it is shown in Fig. 1. A screw 34 bearing against a tail piece of the lever 31 serves to adjust its position.

40 When the circuit is closed through the solenoid or magnet 29, the armature 30 is attracted and the lever 31 is swung on its pivot 32, causing the wedge-shaped end 33 to force the joint 24 of the toggle lever 21 rearward until the links of the lever are out of a straight line and no longer serve to resist the power of the spring 25. The spring thereupon draws the end of the arm 19 upward disengaging the pinion 12 from the gear 13 as above described.

45 The wearing of the parts of the motor, causing the armature to engage the contacts 17, closes an auxiliary circuit supplied by battery 64 energizing a magnet and operating a mechanism, whereby the cut-out is automatically operated and the current is cut off from the motor, thus lessening the chances of injuring the working parts of the motor. The said cut-out mounted 50 on a plate 36, of some insulating material, and located on a suitable part of the car, is provided with a rotatable shaft 37, having the operating handles 38, by means of which the cut-out is operated, it being understood that 55 this is entirely independent of the controller and is adapted to cut off the current therefrom. The plate 36, has mounted thereon three arc-shaped plates 39, 40 and 41, and connected to the plate 40 is the feed wire which passes out through the plate 41 to the controller, 60 as hereinafter more fully described. Carried by the

shaft 37 are three arms 42, 43 and 44, so positioned that they are either in contact with the plates 39, 40 and 41, or out of all contact, as shown in dotted lines in Fig. 4, which fully cuts off the current. The current passes from the plate 40 through the arm 43 to 44 and out 70 through the plate 41 when in the position shown in full lines in Fig. 4. The arm 42 has its outer end of insulating material and has, also, a contact plate 45 carried by the outer end thereof and when the current is on connects the two poles 46 and 47 of an auxiliary 75 circuit, as hereinafter more fully described. Carried by the upper face of the plate 36 is an electro-magnet 48 which connects with the auxiliary circuit and which is normally de-energized and has its armature 49 normally open and engaging a catch 50, carried by the arm 80 51, and held in the position shown in Fig. 4. The arm 51 is pivoted at 52, which is connected to the said auxiliary circuit, and said arm has a coil spring 53 secured thereto, which has a tendency to draw the arm 51 against the contact 54 and close the auxiliary 85 circuit, for the purpose now to be described. The closing of said circuit energizes the magnet 55, carried on the underside of the plate 36, and draws the armature 56 upwardly and throws the opposite end 57 out of the path of an arm 58 carried by the lower end of the 90 shaft 37 and the said shaft is thus free to oscillate. Carried by the rod below the plate is a coil-spring 59 which, when the armature releases the arm 58, causes the rod to rotate and throw the arms 42, 43 and 44 into the position shown in dotted lines in Fig. 4 and thus cut 95 off the current.

Referring to the diagrammatical view in Fig. 7, in my said invention, showing the motor in action, 60 and 61 represent the main wires leading to the motor 3 and the contacts 40' and 41' represent the means by which 100 the current is controlled by the cut-out when it is desired to entirely cut off the power from the car. As heretofore described, when the wearing parts of the motor become so worn as to ground the circuit, a separate auxiliary circuit is closed by the armature 15 engaging the pole pieces 16 and closing the circuit through the wires 62 and 63, which, as before described energizes the electro-magnet 48, releasing the arm 51 and causing the same, by means of the spring 53, to be drawn back, and closing the auxiliary circuit through the 110 poles 52 and 54, simultaneously energizing the solenoid 29 and electro-magnet 55 through mains 60 and 61, and the motor is thus simultaneously allowed to drop with the oscillating movement of the cut-out which through poles 40' and 41' cuts the current from the car. The movement of the cut-out also throws the plate 45 from over the contact points 46 and 47 and breaks the circuit, closing the circuit through poles 40' and 55' and thus preventing the battery or batteries 6 which supply the current to the auxiliary circuit from being 120 run out and becoming useless.

It will be seen by the structure herein shown and described that, should the motor stop by grounding through the wearing of the parts thereof, an auxiliary circuit is closed which is adapted to energize 125 the magnets to operate the entire system of tripping mechanism, whereby the working parts are thrown out of gear with the wheels of the car and the cut-out is simultaneously thrown to cut off the current and prevent further injury to the motor or other parts of the 130

car. This is done to prevent the motor from injury before the cut-out can be thrown by hand and the tripping-mechanism for the motor and its casing is to prevent the motor from being operated by the axle during the hauling or pushing of the car from the place of the grounding back to the stable for repairs, as in the usual practice there is no way for disconnecting the motor from the axle. The automatic feature absolutely prevents the motor from any injury for the moment the motor is grounded the same is disengaged from the axle and the continued running of the car by its own momentum would not in the least affect the motor.

Having thus fully described my invention, what I claim as new and desire to secure by Letters Patent, is:

1. The combination with a vehicle axle, of an electric motor geared therewith, and electrically operated means whereby the motor is thrown out of gear with the axle by the wearing of the armature of the motor.
  2. The combination with a vehicle axle, of an electric motor geared therewith and electrically operated means whereby the motor is thrown out of gear with the axle and the cut-out is thrown.
  3. The combination with a vehicle axle, of an electric motor geared therewith, an electric cut-out controlling the current to the motor, and electrically operated means whereby the motor is thrown out of gear with the axle and the cut-out is simultaneously thrown.
  4. The combination with a vehicle axle, of an electric motor carried by the axle and geared therewith, and means for automatically throwing the motor out of gear with the axle by the wearing of the armature of the motor.
  5. The combination with a vehicle axle, of an electric motor eccentrically carried by the axle and geared therewith, and means operated by the wearing of the armature of the motor for allowing the motor to drop, whereby the same is thrown out of gear with the axle.
  6. The combination with a vehicle axle, of an electric motor eccentrically carried by the axle and geared thereto, means for holding said motor in a horizontal position, and means electrically operated for releasing said holding means by the wearing of the armature of the motor, whereby the same is allowed to drop and is thrown out of gear with the axle.
  7. The combination with a vehicle axle, of an electric motor eccentrically carried by the axle and geared thereto, means for holding said motor in a horizontal position geared to the axle, and electrically operated means for releasing said holding means by the wearing of the armature of the motor, whereby the same is allowed to drop and is thrown out of gear with the axle.
  8. The combination with a vehicle axle, of an electric motor eccentrically carried by the axle and geared thereto, a cut-out for said motor, and electrically operated means for simultaneously throwing the motor out of gear and throwing the cut-out to cut off the current upon the wearing of the armature of the motor.
  9. The combination with a vehicle axle, of an electric motor carried by the axle and geared thereto, means for supporting the motor in a horizontal position, and electrically operated means operated by the wearing of the armature of the motor for releasing said supporting means, whereby the motor is allowed to drop and be thrown out of gear with the axle.
  10. The combination with a vehicle axle, of an electric motor carried by the axle and geared thereto, a pivoted linked member for supporting the motor in a horizontal position, an electrically controlled armature for holding said linked member in such a position so as to hold the motor in a horizontal position, and a circuit closed by the wearing of the armature of the motor for operating said armature for releasing said linked member and allowing the motor to drop out of gear with the axle.
  11. The combination with a vehicle axle, of an electric motor carried by the axle and geared thereto, a pivoted linked member for engaging the motor and preventing the rear end from moving upward, whereby the motor is
- supported in a horizontal position, an armature controlled by magnets for holding said linked member in its extended position, and a circuit closed by the wearing of the armature of the motor for operating said magnets for withdrawing the armature from the linked member, whereby the same may be moved inwardly by the weight of the motor and the same thrown out of gear with the axle.
12. The combination with a vehicle axle, of an electric motor carried thereby and geared thereto, a cut-out for said motor, means whereby the motor is thrown out of gear with the axle, and electric magnets holding the motor in gear with the axle and cut-out closed.
13. The combination with a vehicle axle, of an electric motor carried thereby and geared thereto, a cut-out for said motor, means whereby said motor is thrown out of gear with the axle, electric magnets holding the motor in gear with the axle and the cut-out closed, and an auxiliary circuit closed by the wearing of the armature of the motor for energizing said magnets for releasing the motor and the cut-out.
14. The combination with a vehicle axle, of an electric motor geared thereto, a cut-out for said motor, and means operated by the wearing of the armature of the motor for opening said cut-out.
15. The combination with a vehicle axle, of an electric motor geared thereto, a cut-out having a spring normally holding the cut-out open, an electric magnet having an armature holding the cut-out closed against the tension of the spring, and an electric circuit closed by the wearing of the armature of the motor for energizing said magnet and releasing the cut-out.
16. The combination with a vehicle axle, of a motor carried thereby and geared thereto, an oscillating cut-out having a spring normally holding the cut-out open, an electric magnet having an armature normally holding the oscillating cut-out closed against the tension of the spring, and an electric circuit closed by the wearing of the armature of the motor for energizing said magnet and releasing the cut-out.
17. The combination with a vehicle axle, of a motor carried thereby and geared thereto, means for supporting said motor in gear with the axle, an electrically operated mechanism for releasing said holding means, a cut-out for said motor and an electrically operated means for opening said cut-out simultaneously with the releasing of the motor to disengage the motor from the axle and cut off the current from the vehicle.
18. The combination with a vehicle axle, of a motor carried thereby and geared thereto, electrically operated means for allowing the motor to drop to disengage the same from the axle, an oscillating cut-out having a coil spring normally holding the same open, an armature for engaging said cut-out for holding the same closed, and a circuit closed by the wearing of the armature of the motor for releasing said armature from the path of the cut-out, whereby the current is cut off from the vehicle.
19. The combination with a vehicle axle, of a motor carried thereby and geared thereto, a cut-out for said motor, a spring for holding said cut-out normally open, an armature in the path of said cut-out for holding the same closed against the tension of the spring, a magnet controlling said armature, and an auxiliary circuit closed by the wearing of the armature of the motor for energizing the magnet and releasing the armature and allowing the spring to move the cut-out and cut off the current from the vehicle.
20. The combination with a vehicle axle, of a motor eccentrically carried thereby and geared thereto, means for supporting said motor in a horizontal position in gear with the axle, an armature for holding said supporting means in its normal position, a cut-out for said motor, a spring for holding said cut-out normally open, an armature in the path of said cut-out for holding the same closed against the tension of the spring, and an auxiliary circuit closed by the wearing of the armature of the motor for releasing said armature, whereby the motor is allowed to drop out of gear with the axle and the cut-out is allowed to be opened by the spring, the two movements being simultaneous.
21. The combination with an axle of a vehicle, of a motor eccentrically carried thereby and composed of a ro-

tating armature within a magnetic field composed of a casing and geared to the axle, means for supporting the motor in a horizontal position geared to the axle, an armature controlling said supporting means, and a circuit closed by wearing of the rotatable armature of the motor for releasing said armature controlling the supporting means, whereby the motor is allowed to drop out of gear with the axle.

22. The combination with an axle of a vehicle, of a motor eccentrically carried thereby and geared thereto, means for holding said motor in a horizontal position, and an auxiliary circuit closed by wearing of the armature of the motor for releasing said motor holding means.

23. The combination with an axle of a vehicle, of a motor eccentrically carried thereby and geared thereto, means for holding said motor in a horizontal position, a cut-out for said motor, means for normally holding the cut-out closed against the tension of a spring, and an auxiliary circuit closed by the wearing of the armature of the motor for simultaneously releasing the motor and the cut-out, whereby the motor is thrown out of gear with the axle and the current cut off from the motor.

24. The combination with an axle of a vehicle, of a motor eccentrically carried thereby and geared thereto, a linked member holding the motor in a horizontal position 25 geared to the axle, an armature holding said linked member in a downward position, magnets controlling said armature, an oscillating cut-out for said motor and normally held open by a spring, an armature in the path of said cut-out and adapted to hold the same closed against the tension of the spring, magnets controlling said armature, and an auxiliary circuit closed by the wearing of the armature of the motor for simultaneously energizing the magnets and releasing the motor and the cut-out, whereby the motor is allowed to drop out of gear with the axle and 30 the cut out oscillated and the circuit cut off from the axle.

In testimony whereof we have signed our names to the specification in the presence of two subscribing witnesses.

AUGUSTUS HERATH.
IVER HULTMAN.
